KEY CASE

Harry Stawsky, Brooklyn, N. Y.

Application January 23, 1948, Serial No. 3,970

2 Claims. (Cl. 150—40)

1

This invention relates to an improved keycase. One of the objects of the invention is to provide a keycase with a plate having a plurality of key holding hooks, a strap for moving the plate and hooks in the case toward service position and away from service position, means for securing the strap on the case so that the keys suspended on the hooks will be supported in an closed position within the case.

Another object of the invention is the provision of a key case having closed sides and an open lower end, a key holding plate positioned within the case, a strap secured to the plate to support the keys in the keycase, the keycase having a slot through which one end of the strap slides, and an opening in one end of the keycase through which the other end of the strap slides, so that the keys may be shifted in the case to service use position by pulling on one end of the strap, and may be withdrawn into the case by pulling on the other end of the strap.

Another object of the invention is the provision of a keycase with this combined construction, and a snap fastener having its parts secured to one side of the keycase and to one end of the strap, whereby the strap may be secured to the keycase to retain all of the keys within the keycase.

A still further object of the invention is the provision of a keycase of this general construction, wherein the strap is provided with stops to limit its sliding movement in either direction on the keycase, and prevent complete separation of the strap from the keycase.

A still further object of the invention is to provide the operating strap with wedge shaped portions adapted to frictionally hold the ends of the strap in place in the receiving openings of the keycase.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of the face of the improved keycase, showing the keys in concealed position within the keycase.

Fig. 2 is a plan view of the rear side of the improved keycase.

Fig. 3 is a plan view of the keycase, showing one side wall thereof removed and the operating strap extended.

2

Fig. 4 is a central longitudinal sectional view, taken on line 4—4 of Fig. 1, looking in the direction of the arrows.

Fig. 5 is a plan view of the rear side of a modified form, showing the keys extended for service use.

Fig. 6 is a plan view of the strap, per se, used in the form of the invention shown in Fig. 5 construction.

Referring to the drawings, which illustrate the practical embodiment of my invention, 10 designates a keycase, constructed of leather or similar flexible material, and provided with a front wall 11 and a back wall 12, of equal size. These two walls are secured to each other by marginal plural stitching 13, extending along each side thereof, and along the top edge of the keycase, except at the central upper portion thereof, where an opening 14 is formed between the front wall 11 and the back wall 12. The bottom edge portions 15 of the keycase walls 11 and 12 are wholly unstitched, so that a delivery opening 10a nearly the full width of the keycase is formed.

A flexible leather strap 16 is extended through the top opening 14, and also through the slot opening 17, formed in the back wall 12. This strap 16 is formed with a D-shaped stop 18 on one end thereof, and a D-shaped stop 19 on the other end thereof. The stop 18 is wider than the slot opening 17, so that the strap will not pass entirely through the slot opening, and the D-shaped stop forming end portion of the strap will provide a pull tab on the end of the strap. The strap 16 is also held from complete separation from the opening 14 by means of the D-shaped stop 19, as this stop is wider than said opening, and also forms a pull tab for shifting the strap.

On the flexible leather strap 16 a metal key plate 20 is secured by the rivets 21 and 22. This plate is equipped with a plurality of pivoted key holding hooks 23, on each of which one or more keys 24 may be detachably connected.

The end stop 19 is provided with a button snap coupling element 25, which is adapted to couple with the button snap element 26 attached to the front wall 11, directly below the opening 14.

When the end stop and tab 19 is coupled to the button snap element 26, the key plate 20 and its keys will be supported in their uppermost positions, entirely concealed between the side walls of the keycase. But by separating the pull tab and stop 19 from the coupling element 26 and then pulling on the end stop and tab 18 the key holding plate and hooks, and their keys, will be moved

downwardly toward the delivery opening 10^a, and the keys will be extended below the lower end of the keycase, where they may be identified, and the wanted key selected from the group.

After any one or more keys have been used for the usual service, the tab and stop 19 may be pulled, so that the plate 20 and its keys will be withdrawn into the keycase. To hold the key plate and its keys in the upper part of the keycase, the pull tab and stop 19 is secured to the button snap element 26.

In Figs. 5 and 6, a modified form of the invention is shown, wherein the operating strap 30 is formed with terminal pull tabs and stops 18' and 19'. The portion of the strap 30 adjacent the pull tab 18' is formed with upwardly converging side edges 31, forming a wedge, which is adapted to fit tightly in the slot opening 17, and the portion of the strap 30 adjacent the pull tab and stop 19' is also formed with converging side edge portions 32 forming a wedge which is adapted to fit snugly in the top opening 14'. The pull tab or stop 19' is also equipped with a button snap element 33 which is adapted to engage the button snap element 34 of the keycase 10'.

When a large number of keys are mounted on the movable key plate 20, the button snap may be subjected to excessive strain, and in this condition the wedges formed on the ends of the operating strap 30 serve the very useful purpose of distributing the strain imposed by the weight of the keys upon both walls of the keycase.

My invention provides a keycase wherein a larger number of keys may be quickly concealed between the side walls of the keycase, and brought to immediate service use, without opening the keycase. In this way, all keys are held against entanglement with each other, and quick selection and use may be made.

It is to be understood that this arrangement may be used on keycases of all types and shapes, also on other similar articles.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. Mounting means for a keycase having opposed side walls secured together along both sides and along one end leaving the other end open with a laterally extending slot formed in one of

the side walls midway of its sides and closely adjacent the open end thereof and a restricted opening in the secured ends of the side walls aligned longitudinally with the slot, comprising a strap

5 between the side walls and having its ends slidably projected through the slot and the restricted opening for having keys mounted on the portion thereof between the side walls and between the slot and the restricted opening, means releasably securing the end of the strap which extends from the restricted opening to the outer face of the other side wall, and auxiliary means assisting said releasable securing means in retaining said strap against sliding movement relative to the side walls.

2. Key mounting means for a keycase having opposed side walls secured together along both sides and along one end leaving the other end open with a laterally extending slot formed in one of the side walls midway of its sides and closely adjacent the open end thereof and a restricted opening in the secured ends of the side walls aligned longitudinally with the slot, comprising a strap between the side walls and having its ends slidably projected through the slot and the restricted opening for having keys mounted on the portion thereof between the side walls and between the slot and the restricted opening, means releasably securing the end of the strap which extends from the restricted opening to the outer side wall, and auxiliary means assisting said releasable securing means in retaining said strap against sliding movement relative to the side walls, said auxiliary means comprising spaced wedge-shaped formations on said strap facing the end extended from the restricted opening and at locations to be wedged into the material of the side walls defining the ends of the slot and the restricted opening as the said end of said strap is pulled from the restricted opening for engaging said releasable securing means.

HARRY STAWSKY.
